UNITED STATES PATENT OFFICE.

STEPHEN B. SHELTON, OF SIOUX CITY, IOWA.

SUSPENDERS.

1,290,377.

Specification of Letters Patent.

Patented Jan. 7, 1919.

Application filed November 16, 1915. Serial No. 61,778.

To all whom it may concern:

Be it known that I, STEPHEN B. SHELTON, a citizen of the United States, residing at Sioux City, in the county of Woodbury and

5 State of Iowa, have invented certain new and useful Improvements in Suspenders; and I do hereby declare the following to be a full, clear, and exact description of the invention, such as will enable others skilled 10 in the art to which it appertains to make and use the same.

The primary object of this invention is to improve the general construction of suspenders, by increasing their resilient means 15 and so constructing the same that they will snugly embrace and conform to the body of the wearer, and also admit of the body of the wearer freely assuming different positions.

20 Another object of this invention is to provide suspenders for carrying out the above objects, that will have greater durability than the ordinary suspenders, and will be of simple construction, cheap to manufacture and efficient in operation.

Other objects will appear and be better understood from that embodiment of my invention of which the following is a specification, reference being had to the accompanying drawings forming a part thereof in which:—

Figure 1 is a plan view of the suspenders, in operative position and having one of the rear tabs in section so as to show the 35 interior construction thereof.

Fig. 2 is a side view of the connection for one of the front tabs.

Fig. 3 is a longitudinal section through the connection for the rear tab of the straps 40 of the suspenders.

Referring to the drawings in detail, the numerals 1 and 2 designate the usual shoulder straps of a pair of suspenders, each having one end looped and adjustably connected to the body of the strap by means of the slide 3. The looped end of each of the straps, which are the front ends of the suspenders, when the latter are in operative position, carries a hook 4 which is formed of 45 a single length of wire bent upon itself and formed to provide the bill 5 and has the ends thereof formed to provide a rectangular shaped loop 6 through which the looped end of the strap passes. The bill of each 50 hook has associated therewith a guide member 7, which is formed of a single length of

metal bent upon itself and formed to provide the curved cylindrical shaped eye 8, and the ends of the blank are arranged in overlapping engagement and are provided 60 with aligned openings 9, for the reception of the bill 5 of the adjacent hook.

Slidably mounted in the eyes 8, are arcuate shaped slides 10 the terminals of which are formed to provide eyes 11, which receive the wire loops 12, carried by flexible tabs 13 having button holes 14 therein.

The rear ends of the straps 1 and 2 carry triangular shaped wire loops 15, the ends of which form apices for the triangular loops 70 and terminate in aligned eyes which receive pins 16. The rear ends of the straps 1 and 2 are connected to each other by means of an arcuate shaped slide 17, the opposite ends of which are provided with eyes 18 which 75 receive the pins 16 which pass through the apices of the triangular loops 15.

A second arcuate shaped slide, designated at 19, underlies the slide 17 and is curved in a reverse direction to the curvature of the slide 17 and is connected to the slide by means of a hinge 20. This hinge 20 includes companion portions 21 and 22, each of which is formed of a blank of metal bent to provide an eye 23 and has its ends extending in parallel relations and provided with registering openings. The eye 23 in the portion 21 slidably receives the slide 17 and the eye 23 in the portion 22 slidably receives the slide 19. The ends of the portion 21 are arranged in spaced relation, and the ends of the portion 22 are interposed between the ends of the portion 21 and have openings designated at 24, registering with the openings designated at 25, in the ends 90 of the portion 21 for the reception of a hinged pin 26, the terminals of which are upset against the outer sides of the ends of the portion 21.

Suspended from the slide 19 is a pair of 100 tabs. Each of these tabs comprises a vertically disposed tubular fabric body 27, in which is mounted a coiled spring 28. The lower end of the spring carries a leather strip 29 having a button hole 30 formed 105 therein for the reception of one of the rear buttons on the waist band of the trousers. The upper ends of the springs 28 extend beyond the upper ends of the tubular body 27, and are terminally formed to provide 110 hooks 31, which engage an eye 32 formed by the terminals of the slide 19.

By virtue of employing the particular construction of tabs for the rear end of the suspenders, the resiliency of the suspenders is increased; also by providing the slides 5 10, 17 and 19, and the loose connection between the members 7 and the hooks 5, the body of the wearer can have free movement in all directions, and the straps 1 and 2 will snugly embrace and conform to the shape of 10 the body.

Having thus described my invention what I claim as new is:—

In a suspender construction, the combination with the rear ends of the shoulder 15 straps of the suspenders, loops carried by the ends of the shoulder straps, an arcuate

slide, means pivotally connecting the terminals of the slide to the loops, of a hinge disposed below the slide, the eye of the upper leaf of the hinge loosely receiving the 20 slide, button engaging tabs located below the hinge, an arcuate slide carried by the lower leaf of the hinge, and means pivotally connecting the terminals of the last mentioned slide with the button engaging tabs 25 as and for the purpose specified.

In testimony whereof I affix my signature in presence of two witnesses.

STEPHEN B. SHELTON.
